UNITED STATES PATENT OFFICE.

WILLIAM L. WEBER, OF CHICAGO, ILLINOIS.

COIN-CONTROLLED LOCK.

Application filed May 26, 1922. Serial No. 563,770.

This invention relates in general to locks, and more particularly to the type commonly known as coin controlled locks adapted for use on parcel lockers, cabinets, lockers, and the like where the deposit of a coin is desirable as a prerequisite to manipulation of the lock.

The lock of my present invention is designed to remain normally in unlocked position, permitting access to the locker or other container which the lock controls, the lock being automatically retained in unlocked position with the key so disposed therein that it cannot be removed until the lock has been moved to locked position.

When use of the locker is desired, the user, after the articles to be protected have been deposited in the locker, inserts a coin through a slot in the lock case, which coin, when the key is then turned, serves as a medium to release the lock from its normally unlocked position and acts as an operating link or member to move the bolt into locked position so that the key may be withdrawn and retained by the user as his check until such time as he desires to open the locker, whereupon he inserts the key and unlocks the lock in the usual manner.

One of the primary purposes of my present invention is to provide a lock of the general character indicated, which will be extremely simple in its construction, and will embody a minimum number of parts so that it can be economically manufactured, and one which will be positive and reliable in operation and not apt to get out of order or be subject to breakage or the necessity of repairs.

Another object of my invention is to provide a lock in which complicated locking and control mechanism for normally holding the lock in unlocked position will be eliminated. My present invention comprising, in addition to the locking bolt, but one moving part which is carried directly by the key cylinder and cooperates with the bolt itself to retain the lock in unlocked position until the bolt and this member are disengaged by the action of a coin deposited in the lock.

A further feature of my invention resides in the fact that the two moving parts may be cast or otherwise manufactured at very low cost, and the part which is carried by the key cylinder is capable of being attached to a cylinder of any standard or preferred type, which may be purchased in the open

market, thereby obviating the manufacture of a special type of lock and key.

Another feature of the lock resides in its positiveness of operation, the construction being such that the locking bolt is positively moved into locked position through the intermediary of a coin, its lock action not being dependent upon springs or other mechanism liable to get out of order, but on the contrary, being positive in character, thus ensuring its locking movement, reliability of the lock and obviating dangers of loss of articles from the locker resulting from failure of a lock to operate.

Other objects and advantages of this invention should be readily appreciated as the same becomes better understood by reference to the following description when considered in connection with the accompanying drawings.

Referring to the drawings:—

Fig. 1 is a rear elevation of a lock embodying my invention;

Fig. 2 is a similar view showing the bolt in locked position;

Fig. 3 is a sectional view on the line 3—3 of Fig. 1;

Fig. 4 is a detail perspective view of the operating member carried by the key cylinder.

On the drawings, reference character 5 indicates generally a housing or casing of any preferred construction in which my improved lock is mounted. This casing is preferably provided at one end or side with a flange 7 provided with a slot through which the outer end of the locking bolt 8 reciprocates, this slot thereby serving as one of the guides for the bolt, although obviously other guiding means might be employed, and as herein illustrated the bolt is guided additionally by a guide 9 screwed to the case and embracing the bolt at a point remote from the flange 7.

Within the casing 5, and substantially in alignment with the elongated portion of the bolt 8, there is rotatably mounted a lock cylinder case or housing 11, which may be of any well known or preferred construction, secured to the case by screws 12 or otherwise and adapted to rotatably receive the usual tumblers (not shown) and the key cylinder 13 cooperating therewith.

Upon the outer end of this cylinder, which in the present instance has a centrally projecting portion 14 to add strength to the

structure, there is secured an operating member, illustrated in Fig. 4, comprising a cam-shaped plate 15 apertured at 16 to receive the projecting end 14 of the cylinder, and a coin receiving portion 17 projecting longitudinally of the cylinder outside the housing 11.

The operating member is secured to the end of the key cylinder by screws 18, or other means, and is adapted to partake of the movements of the cylinder which are imparted to it through the instrumentality of the key 19 in the usual manner.

Above the cylinder housing, the case 6 is provided with a slot 21 through which a coin may be introduced, the coin being guided into the receiving slot 22 of the coin receiver 17 by a channel-shaped coin guide 23 disposed upon the inner facing of the casing 5 in alignment with the slot.

The coin receiver is normally retained in alignment with the lower end of the coin guide to receive a coin inserted therein, by a tractile spring 24 attached at one end to the casing 5 and at its opposite end to the cam member 15, as shown in Figs. 1 and 3.

The key cylinder is normally retained in unlocked position and held against locking movement by the engagement of a lug or boss 24 formed on the outer face of the member 15 and adapted to engage with a lug or boss 25 formed on the head 28 of the locking bolt 8 and disposed, when the lock is in unlocked position, in the path of travel of the lug 24, whereby rotative movement of the key cylinder in a counter-clockwise direction, viewing Fig. 1, is limited. A second lug 26 formed on the inner face of the member 15 engages with the tumbler housing 27 of the cylinder case, thereby limiting the movement of the key cylinder in a clockwise direction, viewing Fig. 1, to substantially the position therein shown, wherein the coin receiver is disposed in alignment with the coin chute 23. When the parts are in this position, the cylinder tumblers prevent withdrawal of the key from the cylinder so that the key is therefore locked in the cylinder against removal.

The head 28 of the locking bolt 8 is extended upwardly to dispose its upper extremity in proximity to a coin 29 when positioned in the coin receiver, as shown in Fig. 1. Upon initial rotation of the key cylinder, the coin engaging the opposed end of this head forces the head and its bolt 8 to the left, viewing Fig. 1, to thereby move the lug 25 out of the path of travel of the lug 24, thus permitting continued rotation of the key cylinder until the locking bolt is fully projected into locking position, as shown in Fig. 2. Further movement of the cylinder is then arrested by a lug 31

mounted substantially at the opposite side of the member 15 from the lug 24. When the parts are in this locked position, as illustrated in Fig. 2, the tumblers of the key cylinder and cylinder casing are disposed in alignment so as to permit withdrawal of the key 19. After the coin has passed the lower edge of the bolt head, the bolt is held against retraction by the perimeter of the cam member 15 which engages a flange 32 formed on the bolt head. The coin 29, after the locking movement of the bolt has been effected, will drop by gravity from the receiver 17 through an opening 33 in the case 6 into a chute (not shown) by which it is conducted to a coin collecting receptacle.

The lock will remain in locked position to which it has been moved until the user re-inserts the key 19 in the cylinder, whereupon the key is turned in the opposite direction to restore the cylinder to the normally unlocked position shown in Fig. 1, the bolt being retracted from projected position by a tractile spring 34. During the return movement, the outer edge of the coin receiver 17 will limit the retractive movement of the bolt so that the lug 24 will engage the outer end of the lug 25, and as soon as lug 24 has passed above lug 25, the bolt will be fully retracted to dispose lug 25 in the path of lug 24, thereby locking the device against locking movement until the coin has again been deposited in the slot. A coin, when deposited, serves as an operating instrumentality to project the bolt and clear the lug 25 from the path of lug 24, so that complete locking movement of the parts may be effected. In the absence of a coin the engagement of these lugs will preclude locking movements of the apparatus.

It will be apparent from the foregoing that I have provided a coin controlled lock comprising merely the locking bolt and a member carried by the key cylinder and adapted to receive a coin. When in unlocked position the bolt holds the cylinder against locking movement, and when in locked position the member carried by the cylinder holds the bolt against locking movement. The device is extremely simple in construction and operation and reliable and durable in use, and since it consists of a minimum number of parts danger of getting out of order is practically eliminated.

I claim:

1. In a coin controlled lock, the combination of a reciprocable locking bolt, a rotatable key cylinder, and means carried by said cylinder for moving a coin in an arc to thereby project said bolt and for holding said bolt in projected position after the disengagement of the coin therefrom.
2. In a coin controlled lock, the combi-

- nation of a rotatable key cylinder, a reciprocal locking bolt, a member carried by said cylinder and adapted to cooperate with said bolt, comprising a shoulder engageable with the bolt to prevent rotation of the cylinder in the absence of a coin, a coin receiver adapted through the intermediary of a coin to project said bolt, a second shoulder engageable with said bolt to limit the rotation of said cylinder, and a surface engageable with said bolt to hold the same in projected position.
3. In a coin controlled lock, the combination of a locking bolt, a rotatable key cylinder, and a member adapted to be attached to the end of said cylinder, comprising a cam provided on its outer face with a pair of shoulders and on its inner face with a coin receiver disposed in parallelism with said cylinder.
4. In a coin controlled lock, the combination of a rotatable key cylinder, a locking bolt, and a member mounted on said cylinder and rotatable therewith comprising a coin receiver, a cam and a pair of shoulders whereby the movements of the bolt and its cylinder are controlled.
5. In a coin controlled lock in combination, a locking bolt, a rotatable key cylinder, coin receiving means connected with said cylinder, means on said cylinder normally engaging said bolt whereby said cylinder is held stationary when said bolt is in a normal position, and means connected with said bolt and cooperative with a coin in said receiving means to release said cylinder holding means.
6. In a coin controlled lock in combination, a locking bolt adapted to be moved into and out of locking engagement with a cooperative member, a head and a shoulder on said bolt, a key cylinder adjacent said head and having a cooperative coin receiver, a shoulder on said cylinder adapted to normally engage said bolt shoulder, and a second shoulder on said cylinder spaced from the first said shoulder adapted to be engaged with said bolt shoulder upon insertion of a coin in said receiver.
7. In a coin controlled lock in combination, a locking bolt adapted to be moved
- into and out of locking engagement with a cooperative member, a head and a shoulder on said bolt, a key cylinder adjacent said head and having a cooperative coin receiver adapted to displace said bolt upon rotation of said cylinder after a coin has been inserted in said receiver, and a second shoulder on said cylinder spaced from the first said shoulder adapted to be engaged with said bolt shoulder upon displacement of said bolt.
8. In a coin controlled lock in combination, a locking bolt adapted to be moved into and out of locking engagement with a cooperative member, a head and a shoulder on said bolt, a key cylinder adjacent said head and having a cooperative coin receiver, adapted to displace said bolt upon rotation of said cylinder after a coin has been inserted in said receiver, a second shoulder on said cylinder spaced from the first said shoulder adapted to be engaged with said bolt shoulder upon displacement of said bolt, and means normally urging said bolt toward said cylinder.
9. In a coin controlled lock, the combination of a reciprocating bolt provided with a curved head, a rotatable key cylinder, a coin receiver movable with said cylinder in proximity to said bolt head and cooperative therewith, a boss projecting from said bolt and a pair of lugs carried by said key cylinder at different radial distances from the center of rotation of said cylinder, said lugs being adapted to engage alternately with said boss, one normally, and the other upon insertion of a coin in said receiver.
10. In a coin controlled lock, the combination of a reciprocating bolt, a rotatable key cylinder, a coin receiver carried by said cylinder, a boss on said bolt, a lug carried by said cylinder and adapted to engage said boss whereby the cylinder is normally held against rotation, said bolt being movable from a normal position and said boss being retractable from the path of said lug by means of a coin when inserted in said receiver, and means carried by said cylinder to hold said bolt in its displaced position.

WILLIAM L. WEBER.
